UNITED STATES PATENT OFFICE.

NICHOLAS POWER, OF NEW YORK, N. Y., ASSIGNOR TO NICHOLAS POWER COMPANY, OF NEW YORK, N. Y., A CORPORATION OF DELAWARE.

FILM-WINDING DEVICE FOR MOTION-PICTURE MACHINES.

1,207,211.

Specification of Letters Patent.

Patented Dec. 5, 1916.

Application filed June 8, 1914. Serial No. 843,789.

To all whom it may concern:

Be it known that I, NICHOLAS POWER, a citizen of the United States, and a resident of New York, in the county of Kings and 5 State of New York, have invented certain new and useful Improvements in Film-Winding Devices for Motion-Picture Machines, of which the following is a specification.

10 This invention relates to film reeling mechanism for motion picture machines and has for its object to provide a mechanism in which the film will be retained throughout the entire winding operation under a 15 uniform tension unaffected by the increasing diameter of the reel.

A further object of the invention is to provide a device of this class in which the driving mechanism for winding the reel is 20 controlled by the strip of film, and in which a very slight movement of the film breaks the driving connection and relieving the tension on the film.

25 A further object of the invention is to provide a mechanism of this class which will be of simple and durable construction, and which will afford ample driving power when the driving connection is in operation, but will be easily released upon the desired 30 tension being exceeded without putting undue strain on the film.

35 A further object of the invention will appear from the following description taken in connection with the accompanying drawings, wherein I have illustrated a preferred embodiment of my invention and two modifications of the same.

40 Figure 1 illustrates in side elevation a moving picture machine equipped with my preferred form of reel driving mechanism, and Figs. 2 and 3 show in side elevation and section respectively, a second modification 45 of my invention, and Figs. 4 and 5 are similar views of the third modification of the device.

Referring now to the drawings, particularly Fig. 1, 1 indicates the supporting stand of a moving picture apparatus, which stand preferably comprises a base board 2 from 50 which is suspended the magazine 3 for the film reel 4. The reel 4 is carried by a shaft 5, supported at the intersection of the cross braces 6 of the frame 2. The film feeding

mechanism or machine head is supported on the upper face of the frame 2 as I have indicated in outline at 7, and from this mechanism the film 8 is fed into the magazine through suitable guide rollers 9 to the receiving reel 4.

For driving the receiving reel I attach to 60 the shaft outside of the magazine a disk 10 having a wide smooth periphery or tread adapted to be engaged by a corresponding friction disk 11 having a raw hide or other suitable driving surface. The disk 11 is 65 mounted on a shaft 12 carried by a fork on the end of a depending arm 13 pivoted to the vertical cross bar of the frame. Also attached to the shaft 12 is a sprocket wheel 14 driven by a suitable chain from a sprocket 70 15 attached to one of the revolving shafts of the machine head 7.

The friction disks 10 and 11 are held in driving engagement by a suitable spring which I have shown at 16 attached at one 75 end to the arm and at the other end to a suitable ear on the magazine wall. Also connected to the arm 15 is a link 17 which extends toward the front of the machine and is provided with a pin or axle 18 projecting through a slot 19 in the wall of the magazine and supporting within the magazine a film guiding spool 20. The end of the spool is of sufficient diameter to cover the slot in all positions of adjustment. The 80 position of the spool is such that it deflects the film from its straight path of movement from the guide rollers 9 to the receiving roll as clearly shown in the dotted lines in Fig. 1.

The operation of this mechanism will be 90 obvious from the above description. The normal speed of the reel shaft is sufficient to wind up the film as fast as it is delivered, even when the reel is of its smallest diameter. As the diameter of the reel increases 95 the pull on the film becomes greater, and when the pull on the film exceeds the tension of the spring, the link 17 will be pushed to the left and swing the disk 11 out of engagement with the disk 10, thereby breaking the driving connection. As soon as the tension is relieved by the film being fed into the magazine, the spring will draw the friction disks together again. By having the driving faces of the friction disk of considerable width ample driving friction is pro- 100 105

vided without necessitating a spring of undesirable strength. As the driving connection is broken by the slightest movement of the disk 11, the film spool 20 has very little movement and consequently there is not an appreciable amount of slack in the film to be taken up with a jerk as in the tension devices heretofore constructed. In fact the engagement and disengagement of the driving disks follow in such rapid succession that the effect is the same as a continuous drive of the proper speed to wind the film under the desired tension.

In Fig. 2 I have shown a modified form 15 of the invention in which the friction disk 11^a, corresponding to the disk 11 of the previously described device is mounted on an arm 22 whose lower end is provided with a hub or strap encircling an eccentric 23 rotatably mounted on the extension 24 of the stationary journal of the reel shaft. The arm 22 is provided with a pin 25 which works in a slot in the magazine wall whereby the arm is held against rotation but is permitted 25 a slight vertical movement to bring the friction disks 10 and 11^a into and out of contact.

The eccentric 23 is provided with an arm 26 extending upwardly and toward the front, and pivoted to the end of the arm is the link 17 carrying the film guiding spool 20 similar to that employed in the previously described form of device. The arm 26 is also provided with a spring 27 tending to move 30 the link and spool against the tension of the film. The operation of this form of device will be obvious from the above description. As the reel takes up the film more rapidly than it is fed into the magazine the tension 35 of the film will shift the spool 20 toward the rear of the machine thereby turning the eccentric 23 and raising the disk 11^a out of contact with the disk 10 allowing the reel to stop until sufficient slack is provided in the 40 film to permit the spring 27 to turn the eccentric in the opposite direction and bring the driving disks again into contact.

In the modification of the device illustrated in Figs. 4 and 5 I employ in place 45 of the friction disks 10 and 11 a friction clutch of the disk type having ample area to provide a smooth driving connection. The friction disks I have indicated at 30 and 31 respectively and one of the disks is preferably provided with a leather or other suitable friction face. The disk 30 is loose on the reel shaft 5 and has keyed to its hub a driving sprocket 32. A collar 33 is attached to the end of the shaft and prevents the 50 clutch disk and sprocket being forced off the shaft. The other clutch disk 31 is attached to the shaft by a pin passing through a slot in the shaft to permit a sufficient sliding movement of the clutch disk to disengage 55 the friction faces. A spring 34 is mounted

on a shaft between the disk 31 and the collar 35 on the shaft to hold the clutch members together with sufficient pressure to provide the desired driving tension.

The disk 31 is of larger diameter than the 70 corresponding disk and is tapered at its periphery to provide a conical flange 36. Co-operating with the flange 36 is a conical disk 37 rotatably mounted on a stud 38 set in a block 39 slidably mounted in suitable 75 guides on the magazine wall above the reel shaft. The block 39 is reciprocated by means of a link 40 carrying at its free end the tension spool 20, which as in the previously described construction is shifted toward the 80 rear of the machine when the desired tension of the film is exceeded.

The normal position of the disk 37 is in front of the vertical diameter of the disk 31 so that as the block 39 moves rearwardly 85 under the tension of the film the disk 37 will engage the conical extension 36 and force the clutch disk out of engagement against the tension of the spring 34. As soon as the disk is out of engagement the 90 shaft 5 will stop allowing the disk 30 to revolve idly on the shaft.

Having thus described my invention, what I claim and desire to secure by Letters Patent is:—

95

1. In a motion picture machine, the combination of a receiving reel for the film, a magazine inclosing the same, means for driving the same comprising driving and driven members, and means for connecting and disconnecting said members consisting of a film guiding spool having its axle projecting through a slot in the wall of the magazine and a link without the magazine connected to said spool and operating to disconnect said members upon movement of the spool produced by the tension on the film.

2. In a moving picture machine, the combination of a winding reel for the film, a magazine inclosing the same, means for driving the reel comprising a positively driven continuously rotatable friction disk, a second friction disk connected to said reel to drive the same, said disks being relatively movable, a spring for holding the disks in driving engagement, and means for separating said disks against the tension of the spring, comprising a link operatively connected to the movable disk, a film guiding spool movably mounted on the side wall of said magazine, and connected to said link to shift the link when the tension on the film exceeds the tension of the spring.

3. In a moving picture machine, the combination of a receiving reel for the film, a magazine inclosing the same, a shaft on which the reel is mounted projecting through the wall of the magazine, a disk mounted on said shaft having a peripheral friction driving surface, a similar disk mounted for 100

movement toward and from said first mentioned disk, means for positively driving said second disk, a spring for holding the peripheries of said disks in frictional driving engagement, and means controlled by the tension of the film within the magazine for radially separating said disks.

Signed at New York, in the county of New York, and State of New York, this 26th day of May, 1913.

NICHOLAS POWER.
